1,536,350

UNITED STATES PATENT OFFICE.

LEWIS E. MORRISON, OF NEWARK, NEW JERSEY, ASSIGNOR TO KLYMAX FEEDER COMPANY, A CORPORATION OF NEW JERSEY.

PRINTING MACHINE.

Application filed December 18, 1923. Serial No. 681,318.

To all whom it may concern:

Be it known that I, LEWIS E. MORRISON, a citizen of the United States, and resident of Newark, in the county of Essex and 5 State of New Jersey, have invented certain new and useful Improvements in Printing Machines, of which the following is a specification.

This invention relates to paper feeding 10 mechanisms for printing machines of the Chandler & Price and similar types, such as is disclosed in my U. S. Letters Patent No. 1476829 dated December 11, 1923, to which reference is made for a more detailed de- 15 scription than is necessary for a complete understanding of this invention.

In the said patent there is disclosed a paper feeding mechanism adapted to be swung away from the printing machine in 20 order to permit hand feeding of the paper and for other purposes.

It is an object of this invention to provide a novel and improved mechanism for moving the paper feeding mechanism to 25 one side of the printing machine for the purpose set forth. To this end my invention is embodied in a paper feed mechanism arranged and constructed as herein- 30 after set forth and as illustrated in the accompanying drawing in which—

Figure 1 is a side view of a press equipped with a paper feed mechanism embodying the invention, with parts broken away and omitted.

Figure 2 is a view looking from the left in Figure 1 with parts omitted and broken away.

Only so much is shown of the printing machine as is necessary to understand this 40 invention. In this instance there is shown a Chandler & Price job press identified by the frame 3, the platen 4 and the form carrier 5. The paper feeding mechanism is identified by the feed table 6 carrying the 45 paper support 7 on which rests the paper 8. The means for transferring the paper to the platen comprises the parts 9, operated by levers 10, all as more particularly set forth in the said patent and also in my 50 U. S. Patent Number 1,393,036.

For the purpose of this invention the aforesaid elements will be called a paper feeding mechanism both in the specification and in the claims.

55 Referring now more particularly to the

subject matter of this invention, the reference numeral 11 denotes a side bracket secured to the frame 3 and which is substantially similar to a bracket serving a similar purpose shown in the patents aforesaid. 60 The bracket 11 has a rear upstanding arm 12 forming a shoulder 13, and a forward upstanding arm 14 having an inclined upper surface 15 and formed with an integral depending lug 16. 65

The paper feeding mechanism, more specifically the feed table 6, is provided with an operating hand lever 17 rigidly secured thereto as by a bolt 18 or other means. The entire feeding mechanism including the 70 operating hand lever is pivoted at 19 to a slide bracket 20 having a slide foot 21. The latter slides in a guide way 22 formed on the front of the lug 16.

Normally the feed table 6 rests on the said 75 inclined bracket surface 15 with its rear lower edge resting on the shoulder 13 and a similar shoulder 23 on a bracket 24 on the left side of the press, see Figure 2. In this position the slide bracket 20 is close 80 to the bracket arm 14 as shown in dotted lines in Figure 2, and the feeding mechanism represented by the feed table 6 is in position over the press. When thus placed, the feeding of the press is automatic and is 85 performed by the paper feeding mechanism and its associated and operating parts, all of which are not shown or described in this specification.

When, however, it is desired to hand feed 90 the press, or to make ready or for other reasons to get at the press, the feeding mechanism is slid sideways away from the press by moving the slide bracket 20 from the position shown in dotted lines in Figure 2 to the position shown in full lines 95 therein.

This is accomplished by the following 100 means. A pulley bracket 26 is secured to the fixed guide way 22 and a pulley 27 is mounted on said bracket. A cable 28, for instance a piano wire or other non stretchable cable wire or cord is wound around said pulley and attached to the slide bracket 20 at 29 and to the slide foot 21 at 30. Consequently when said pulley 27 is rotated 105 by the operator by means of the handle 31, the cable 28 is wound on said pulley and the slide foot is drawn across the press within the guide way 22 and the slide 110

bracket is moved likewise carrying the feeding mechanism along.

However, before operating the feeding mechanism as described, it must be detached 5 from its operating parts such for instance as are herein represented by the levers 10. At this point reference is again made to the aforesaid patents for a full discussion 10 of the elements and operation of the paper feed mechanism.

Before moving the feeding mechanism it is therefore lifted as indicated by the dotted position of the feed table 6 in Figure 1.

This movement is accomplished by the 15 operator grasping the hand lever 17 and pushing it to the right in Figure 1 around the pivot 19. In either one of its two positions, the hand lever is locked to the slide bracket by means of a spring pressed pin 33 20 adapted to enter either one of two holes 34 and 35 in the slide bracket 20 as will be understood. Before operating the hand lever the operator pulls said pin out of its hole, and when the new position is reached the pin 25 automatically snaps into the other hole and locks the lever to the bracket. For the purpose of perfect register between the feeding mechanism and the fixed bracket arm 14, the latter is provided with a hole 36 into which 30 a pin 37 on the slide bracket is adapted to enter.

After the feeding mechanism has been removed as shown in Figure 2, the press may be hand fed from a feed board 38 placed in 35 a socket 39, see Figure 1.

To sum up: Normally the paper feeding mechanism is in position as shown in Figure 1 in full lines and in active operative relationship with the press. It is removed 40 and brought into inoperative relationship with the press by first swinging it upward around the pivot 19 when it automatically is locked by the pin 33 entering the hole 35. Thereafter the pulley 27 is rotated to operate 45 the cable 28 to draw the feeding mechanism to the one side. The reverse movement brings the feeding mechanism back into operative relationship with the press. The cable on the pulley serves also as a locking 50 means for the slide bracket because the same cannot be moved sidewise unless the pulley is rotated.

While I have disclosed my invention in its preferred form it is obvious that changes 55 in the detailed construction may be made without departing from the principles of the invention and the scope of the appended claims.

I claim:—

60 1. The combination with a printing press, of a paper feeding mechanism therefor, a member secured in sliding relationship to said press, means for mounting said mechanism on the said member and means for

sliding the latter to one side of the press to 65 remove said mechanism from operative relationship to the press.

2. The combination with a printing press of a paper feeding mechanism therefor, a member secured in sliding relationship to 70 said press, means for pivoting said mechanism on the said member to operatively connect and disconnect said mechanism from said press, means for operating said mechanism on the pivot thereof and means for 75 moving said member towards and away from said press for the purposes set forth.

3. The combination with a printing press, of a paper feeding mechanism therefor, supporting means for said mechanism, guiding 80 means in said supporting means, a member adapted to slide in said guiding means, means for pivoting said mechanism on the said member, means for operating said mechanism on its pivot into one of two pre-determined positions with respect to the said press and means for operating said member in the said guiding means when the said feeding mechanism has been operated into one of the aforesaid two positions to move 85 said mechanism away from operative relationship with the said press.

4. The combination with a printing press, of a paper feeding mechanism therefor, a bracket to which said mechanism is pivoted, means for movably supporting said bracket on the said press and means for sliding 90 said bracket away from said press to remove the said feeding mechanism therefrom to gain access to the press, said last 95 mentioned means also serving to move the bracket towards the press to connect the feeding mechanism therewith.

5. The combination with a printing press, of a paper feeding mechanism therefor, a 105 guide way secured to said press, a member movable in said guide way, means for pivoting said mechanism on the said member, means for operating said mechanism on said member to connect or disconnect the mechanism from operative relationship with the 110 press and means for moving said member in the said guide way to remove said feeding mechanism from the press.

6. The combination with a printing press, 115 of a paper feeding mechanism therefor, a guide way secured to said press, a member movable in said guide way, means for pivoting said mechanism on the said member, means for operating said mechanism on said 120 member to connect or disconnect the mechanism from operative relation with the press and normally operable means interposed between said press and member for moving said member and the said paper feeding 125 mechanism to one side of the press.

LEWIS E. MORRISON.
